Attorney.

UNITED STATES PATENT OFFICE.

THOMAS CAPPARELLA, OF NEW YORK, N. Y.

PERMUTATION ELECTRIC SWITCH.

1,310,605.

Specification of Letters Patent. Patented July 22, 1919.

Application filed February 6, 1919. Serial No. 275,350.

To all whom it may concern:

Be it known that I, THOMAS CAPPARELLA, a citizen of the United States, residing at New York, in the county and State of New 5 York, have invented certain new and useful Improvements in Permutation Electric Switches, of which the following is a full, clear, and exact specification.

This invention relates to permutation electric switches, and has for its object to simplify and improve tumbler disks and the electric connections to and through them, so that such switches may be manufactured at a reduced cost and give superior results in 10 use.

A special object is to combine the step by step retaining arms for the tumbler disks with the circuit connections so that said arms will serve the double function and 15 simplify the construction and reduce the number of necessary parts. Another object is to shorten the connectors which are embedded in the disks, and to arrange all of the contact arms on the same side of the device. Other objects will appear as the description proceeds.

The invention will be first hereinafter described in connection with the accompanying drawings, which constitute part of this 20 specification and then more specifically defined in the claims at the end of the description.

In the accompanying drawings, wherein similar reference characters are used to designate corresponding parts throughout the 25 several views:—

Figure 1 is a front elevation of the switch casing, showing the dial, pointer and operating knob.

Fig. 2 is a central section through the switch casing from front to back, showing the tumbler disks and contact arms in elevation.

Fig. 3 is a section through the disks and arms as well as the casing, the section being taken on the line III—III of Fig. 2, and showing the circuit wires connected to the single end arms at the front and back of the device.

Fig. 4 is a detailed face view of one of

the tumbler disks, showing the radial grooves therein, and

Fig. 5 is a rear elevation of the switch with the back of the casing removed.

The casing of the switch is preferably 55 made round, as shown in Figs. 1 and 5, and comprises front and back portions 1 and 2, respectively, having slip connection at 3. It will be understood that the switch may be used wherever it can be utilized to advantage, but it is especially designed for controlling the power circuits of automobiles to prevent the unauthorized use of 60 cars.

A frame 4 has its legs secured to the front 65 member 1 of the casing, as by solder 5, and a shaft 6 is journaled at 7 in said front member 1 and at 8 in said frame. On the front end of the shaft 6 there is an operating knob or handle 9 on the outside of the 70 casing, while within said casing and between the front portion 1 thereof and the frame 4 there are arranged a plurality of tumbler disks, three being shown at 10, 11 and 12. One of said disks, the middle one as shown, 75 has a hub portion 110 through which a clamping screw 13 is passed to fix it to the shaft 6. The front disk 10 is suitably spaced from the dial 20 by a washer 14. The disks 10 and 11 may be spaced apart 80 by the hub 110, while the disks 11 and 12 are spaced apart by one or more washers also indicated at 14, and another of said washers is placed between the rear disk 12 and the frame or bracket 4. A washer 15 85 may be placed between the rear face of the frame 4 and the back member 2 of the casing.

The adjacent faces of the disks are 90 equipped with axially projecting pins or lugs 18 which may be placed at any desired points on said disks for causing the end disks 10 and 12 to be turned at the proper times by the middle disk 11, as is common in permutation devices, the end disks being 95 loosely mounted on the shaft 6 on which the middle disk 11 is secured to turn therewith by the screw 13 or otherwise. The marginal portion of one lateral face of each disk is formed with radially arranged grooves 16, 100

and the connectors 17 are placed respectively at the bases of one of said grooves in each disk, as shown in Figs. 3 and 4. A pointer 19 is carried by the shaft 6 in front 5 of the dial 20 and preferably below a crystal 200 for indicating the movements of said shaft which is rotated by means of the knob 9 to adjust the tumbler disks to the required combination.

- 10 Mounted in the casing, preferably on one end portion of the frame or bracket 4 is a plate or strip of insulating material 23 on which are mounted contact arms 24, 26, 27, 29, 30 and 32. The contact arm 24, at the 15 extreme rear or back of the casing, is attached to the insulating plate 23 by a lump 25 of conducting material, such as solder or other metal, and to it is connected one of the circuit wires 21. The contact arms 20 26 and 27 are both attached to a lump 28 of conducting metal which is spaced from the lump 25 along the insulating plate 23. The contact arms 29 and 30 are similarly both connected to a lump 31 of conducting metal 25 which is spaced along the insulating plate 23 from the lump 28. The contact arm 32 is connected to a lump 33 of conducting metal which is attached to the insulating plate 23 in spaced relation to the lump 31, 30 and to said arm is connected the other circuit wire 22, as shown in Fig. 3. It will thus be seen that the contact arms 26, 27 and 29, 30 are electrically connected together in pairs, while the contact arms 24 and 32, 35 which are connected to the circuit wires, are insulated from said pairs of connected arms, and that the said connected pairs of arms are insulated from each other by the plate 23.

The contact arms bear upon the opposite 40 lateral faces of each of the tumbler disks, the arm 24 engaging the rear face of the disk 12, the arm 26 engaging the front face of the same disk, the arms 27 and 29 engaging the rear and front faces, respectively, 45 of the disk 11, and the arms 30 and 32 engaging the rear and front faces, respectively, of the disk 10. As shown, the front face of each disk has the radial grooves 16 in its marginal portion, and the free ends of the 50 arms 26, 29 and 32 are offset at 34 to seat in said grooves and engage them in succession for retaining said disks in a step by step movement according to the dial. All 55 of the arms may be resilient so as to insure their contacting firmly with the faces of the disks. The arms 24, 27 and 30, which engage the smooth rear faces of the disks, may also be offset slightly, as at 35, to insure their making close contact with the connectors 17 60 where they are flush with said rear surfaces of the disks. The offset ends 34 of the other arms are adapted to contact with the connectors 17 where they are arranged at the bases of one of the grooves 16 in each disk,

so that when the disks are turned to agree 65 with a predetermined combination to bring the connectors 17 of all of the disks into contact with the arms which engage the opposite faces of all of the disks, the circuit will be completed through said arms, connectors and lumps 25, 28, 31 and 33 of conducting metal from one of the circuit wires 21 to the other of said circuit wires 22. The circuit may be traced as follows: wire 21, lump 25, arm 24, connector 17 in the disk 12, 70 arm 26, lump 28, arm 27, connector 17 in disk 11, arm 29, lump 31, arm 30, connector 17 in disk 10, arm 32, lump 33, wire 22. The arms 26 and 27, and arms 29 and 30 75 are shown in contact along their middle portions, so that the circuit can pass directly from arm 26 to arm 27 and from arm 29 to arm 30, instead of passing through the lumps 28 and 31, but the results will be the same as if said arms were not in direct 80 contact.

It will be observed that the offset ends 34 of the arms which engage the front faces of the several disks serve the double function of conductors in the circuit, as they 90 contact with the connectors 17 and carry the current, and of step by step retainers for the disks or tumblers of the permutation device. When said offset ends of the arms are moved from one groove 16 to another 95 they make sufficient noise and exert sufficient force on the shaft or stem of the permutation device to enable one who has knowledge of the combination to manipulate the switch without seeing the dial. It is obvious, of 100 course, that the combination may be changed by moving the pins 18 on the disks or changing the positions of the connectors 17 to different grooves 16 in said disks.

Having thus described my invention, what 105 I claim as new and desire to secure by Letters Patent of the United States is:—

1. In a permutation electric switch, the combination with a plurality of disks of insulating material co-axially arranged and 110 spaced apart each having radial grooves in one of its lateral faces, of connectors extending through said disks respectively from one lateral face to the other and arranged at the bases of one of the grooves in each 115 disk, and contact arms extending between said spaced disks and engaging each lateral face of each disk for completing a circuit through said connectors when the disks are arranged to bring them in contact with said arms, the arms which engage the notched faces of the disks having offset portions to co-operate with said notches to retain said disks in step by step positions.

2. In a permutation electric switch, the 125 combination with a plurality of disks of insulating material co-axially arranged and spaced apart, of connectors embedded in

said disks and extending through them from one lateral face to the other of each, contact arms arranged parallel to one another and having their ends engaged with the opposite 5 faces of each disk, there being two arms extending between each pair of adjacent disks, one of said arms engaging each of said adjacent disks, and a single arm engaging the outer face of each of the end disks, electric 10 connections between the two arms of each

of said adjacent pairs, insulating means between said adjacent pairs of arms and the other pairs, and circuit connections to the single end arms, whereby a circuit will be completed through the arms and connectors 15 when the latter are brought into contact with said arms.

In testimony whereof I have signed my name to this specification.

THOMAS CAPPARELLA.
